UNITED STATES PATENT OFFICE.

PETER SORENSEN, OF BROOKLYN, NEW YORK.

LAMP-GUARD.

No. 900,439.

Specification of Letters Patent.

Patented Oct. 6, 1908.

Application filed December 19, 1907. Serial No. 407,124.

To all whom it may concern:

Be it known that I, PETER SORENSEN, a citizen of the United States, and a resident of Brooklyn, in the county of Kings and State of New York, have invented certain new and useful Improvements in Lamp-Guards, of which the following is a specification.

My invention relates to guards for incandescent electric lamps, the object being to provide a simple, strong and efficient device from which the lamps may be easily and quickly removed and replaced.

To these ends my invention consists in the details of construction and combinations of parts hereinafter more particularly described and then specified in the claims.

In the accompanying drawings, Figure 1 illustrates in side elevation a lamp-guard 10 constructed in accordance with my invention. Fig. 2 is a central longitudinal section of the same on the line *x* *x* on an enlarged scale, the lamp being shown in side elevation. Fig. 3 is a plan view of the same looking at 25 the handle side of the base. Fig. 4 is a horizontal section on the line *Y* *Y*, Fig. 2, the lamp being removed.

1 indicates a handle provided with a central longitudinal passage 2 within which at 30 its upper end is secured a sleeve 3. A circular plate 4 is seated upon the upper end of the handle 1 and clamped thereon by any suitable means such as a washer 5 preferably of insulating material and nut 6 having a 35 threaded engagement with the part of the sleeve 3 which projects from the handle 1. After the plate 4 has been secured to the handle by the nut and washer the end of the sleeve 3 still projects upward from the nut 40 6, and to it is secured the incandescent lamp 7 as is usual in the art.

The handle and plate secured thereto form the supporting means of the device for the lamp and the guard. The guard proper is 45 adapted to be removably secured to the supporting member of the device and comprises a cage made up of a plurality of parallel vertical wires 9 mounted at their lower ends to a base consisting preferably of a ring 8, the 50 inner diameter of said ring coinciding closely with the diameter of the plate 4, said plate being adapted to be inserted within the ring 8. The wires 9 pass up through a reinforcing ring 10 preferably disposed below the 55 glass portion of the lamp 7 so as not to obstruct any light therefrom and are bent over

at their upper ends and secured to a hub 11 preferably by threading the same radially therein as well known in the art. Also secured to the hub 11 is a hook 12 to provide means whereby the lamp may be hung wherever desired. 60

Secured to the hub 11 within the cage is a loop of spring metal 13, provided with a hole 14 centrally located with regard to the cage 65 which is adapted to receive the sealed tip 7 of the bulb of the lamp. This loop 13 bears against the end of the bulb of the lamp thus supporting this end of the lamp and serves to centrally locate it and prevent the lamp 70 from hitting the wires of the cage and being broken if the lamp should become loosened from its socket as frequently happens.

The wires 9 are secured to the base 8 at their lower ends preferably by upsetting the 75 same and thus riveting them to the base as is usual in the art. A plurality of tongues 15, 16 projecting radially inward from the base or ring 8 form clamping means by which the guard is secured to the supporting 80 plate 4. The tongues 15, 16 are preferably formed from a single strip doubled upon itself and located one above and the other below the ring 8 and secured thereto by the riveting of the ends of the wires 9. The 85 tongue 16 located on top of the ring 8 projects further inward than the tongue 15 located on the bottom of the ring for reasons to be presently set forth. A plurality of recesses 17 conforming in number, location 90 and size with the projecting free end of the tongues 15 are provided in the periphery of the plate 4 so that the free ends of the tongues 15 will pass through the recesses and by turning the handle and plate 4 the ring 8 and guard supported by it will be held fast 95 to the supporting part of the device. The free ends of the tongues 16 projecting further than the depth of the recesses 17 limit the inward movement of the plate 4 and cause it 100 to register with the ring 8.

Referring more particularly to Figs. 3 and 4, 18 indicates a detent pivotally mounted upon the plate 4 in such position that its free end will engage the side of the free end 105 of one of the tongues 15, the detent being held in this position by a spring 19 preferably also mounted on the plate 4 and acting on the free end of the detent 18. The back and forth movement of the detent into and out of engagement with the tongue 15 is 110 limited by a laterally projecting pin 20.

22
 cured to the detent working in a slot 21 located in the plate 4, the said slot being of the right size so that it will stop the outward movement of the detent when its free end has engaged the side of the tongue and stop the inward movement when the detent is sufficiently free from the tongue to permit movement of the plate 4 thus preventing unnecessary weakening of the spring 19 due to 10 too great a movement of the detent. In securing the two members of the device together the recesses 17 are registered with the tongue 15 and the plate 4 turned in the direction of the arrow *a*, the free end of the 15 detent 18 riding on the free edge of the tongue 15 until the plate has been revolved sufficiently far to allow it to be forced free and in position to engage the side of the tongue should the plate be revolved in the 20 reverse direction or that of the arrow *b*. A stop 22 on the plate 4 engages the other side of the tongue when the detent has revolved beyond the tongue and prevents further movement of the plate in the direction of the 25 arrow *a*. The supporting part of the device and the guard thus become locked together and cannot be separated until the detent has been swung clear of the tongue and the plate 4 turned until the recesses register 30 with the tongues 15 when the parts can again be separated.

While I prefer to have the stop 22 operate upon the same tongue 15 as the detent operates upon, it is obvious that it might be disposed to operate on any other tongue or on 35 one of the tongues 16 without departing from the spirit of my invention. Also my invention is equally applicable to a device wherein the socket for the lamp is located 40 within the handle instead of being secured to the end as herein shown.

What I claim as my invention is:

1. In a lamp guard, the combination of a 45 plurality of wires forming a cage, a base provided with a central opening secured to the ends of said wires, supporting means comprising a handle and a plate secured thereto adapted to register with the opening in said base and adapted to be revolved 50 therein, and inwardly projecting clamping members formed of a single piece of metal bent over the edge of said base and adapted to engage said plate on both faces, said members being secured to said base by the 55 ends of said wires.

2. In a lamp-guard the combination of a 60 plurality of wires forming a cage, a base provided with a central opening secured to the ends of said wires, long and short 65 inwardly projecting clamping members secured to the base by said wires, and consisting of a single piece bent back upon itself over the outer edge of said base, a supporting handle, and a plate secured thereto provided with recesses in its periphery for the

passage of the short clamping members, said plate being adapted to be revolved in the opening in said base to bring said recesses into and out of alignment with said clamping members.

3. In a lamp-guard the combination of a plurality of wires forming a cage, a base provided with a central opening secured to the ends of said wires, long and short clamping members secured to the base by said 75 wires, a supporting handle, a plate secured to said handle provided with recesses in its periphery for the passage of the short clamping members, said plate being adapted to be revolved in the opening in said base to 80 throw said recesses out of alignment with said clamping members to secure said cage, a fixed stop and a pivotally mounted movable stop operating on said clamping members to lock said plate and said cage. 85

4. In a lamp-guard the combination of a plurality of wires forming a cage, a base provided with a central opening secured to the ends of said wires, long and short clamping members secured to the base by said 90 wires, a supporting handle, a plate secured to said handle provided with recesses in its periphery for the passage of the short clamping members, said plate being adapted to be revolved in the opening in said base to 95 throw said recesses out of alignment with said clamping members to secure said cage, a fixed stop on said plate operating on one of said clamping members adapted to prevent said plate being revolved in one direction and a spring-actuated movable stop operating on one of said clamping members adapted to prevent said plate being revolved in the opposite direction.

5. In a lamp guard the combination of a 100 plurality of wires forming a cage, a base provided with a central opening secured to the ends of said wires, long and short clamping members secured to the base by said 105 wires, a supporting handle, a plate secured to said handle provided with recesses in its periphery for the passage of the short clamping members, said plate being adapted to be revolved in the opening in said base to throw said recesses out of alignment with 110 said clamping members to secure said cage, a fixed stop on said plate operating on one of said clamping members adapted to prevent said plate being revolved in one direction and a detent mounted on said plate 115 operating on one of said clamping members adapted to prevent said plate being revolved in the opposite direction.

Signed at New York in the county of New York and State of New York this 17th 125 day of December A. D. 1907.

PETER SORENSEN.
